UNITED STATES PATENT OFFICE

ALLEN B. COOKE, OF DANVILLE, ILLINOIS, ASSIGNOR TO UNITED AUTOGRAPHIC REGISTER CO., A CORPORATION OF ILLINOIS

AUTOGRAPHIC REGISTER

Original application filed February 16, 1931, Serial No. 516,198. Divided and this application filed July 13, 1931. Serial No. 550,536.

This invention relates particularly to autographic registers of the type in which the duplicating strips are drawn from a suitable source of supply across a platen, upon which tickets, or slips, are filled in and a record (original or copy) stored in the machine.

The present application is a division of application Serial No. 516,198, filed February 16, 1931, and relates more particularly to a constantly operated feed mechanism which acts intermittently to feed flexible strips a determined distance.

The invention is applicable to various kinds of machines of the general character mentioned above. It may be used very advantageously in the type of machine having provision for storing the original slips and discharging the copies through a lateral discharge orifice. It may be employed, also, in machines of the type where the original and a desired number of copies are discharged from the machine and the lowermost copy is stored in the machine.

In the embodiment shown in the accompanying drawings, the invention is applied to a side-delivery machine which extrudes the copies and retains the original.

In the drawings:

Fig. 1 is a longitudinal vertical sectional view of an autographic register embodying the invention; Fig. 2, a broken transverse vertical sectional view on an enlarged scale of the feed-mechanisms, taken as indicated at line 2-2 of Fig. 1; Fig. 3, a broken transverse vertical sectional view on an enlarged scale, showing one of the feed-mechanisms in a different position from that shown in Fig. 2; Fig. 4, a broken longitudinal vertical sectional view, taken as indicated at line 4 of Fig. 2; Fig. 5, a similar view taken as indicated at line 5 of Fig. 3; Fig. 6, a broken longitudinal elevational view of the mechanism for locking the crank; and Fig. 7, a broken vertical sectional view taken as indicated at line 7 of Fig. 6.

In the embodiment illustrated, A designates a casing, or frame, provided with a supply compartment A', a platen A², a cover A³ adapted to partially inclose the platen,

a filing compartment A⁴, and a closure A⁵ affording an entrance to the compartment A⁴; B, main feed-mechanism for drawing the duplicating strips from the supply compartment over the platen A²; C, clamping and cutting mechanism adapted to hold and sever the record strip; D, auxiliary feed-mechanism for projecting the record copy into the filing compartment A⁴; E, a laterally-open delivery chute through which the copy-strips are delivered; and F, a lock for the closure A⁵.

The casing A is of known construction. The platen A² and the cover A³ are pivotally connected at one lateral edge with the upper portion of a side wall of the casing, in the usual manner. The closure A⁵ is connected at the bottom edge with the lower front end portion of the casing by a transverse pivot 1. The base-portions of the compartments A' and A⁴ are inclined downwardly and rearwardly to reduce the required head space and to provide a downwardly extending slide in the compartment A⁴ for the record slips.

The feed-mechanism B is similar to that described in the Jensen application, Serial No. 289,821, filed July 2, 1928, and comprises an upper feed-roll 2, and a lower feed-roll 3, which have intermeshing gears 4 and 5. The feed-rolls are provided with normal feed-disks 2^a and 3^a and with initial feed segments 2^b and 3^b. The upper feed-roll is mounted in a transverse housing 6, one end of which is pivotally supported at 7 and the other end is equipped with a releasable catch 8. The feed-rolls are driven by the crank-shaft 9, through the medium of gears, as will be explained more fully below. The shaft 9 is equipped with a crank 9^a which co-operates with a latch-device or withdrawable stop 10, shown in Figs. 6 and 7.

The cutter-mechanism C is shown with a clamping bar 11 and a cutter-blade 11^a. This mechanism, also, is similar to that shown in Jensen application Serial No. 289,821.

In the cycle of operations of the machine, the main feed-mechanism B feeds the strips a form-length and the strips then remain at rest until the severing and filing are effected.

The auxiliary feed-mechanism D, accordingly, is designed to effect feeding of the severed slips, seriatim, at proper intervals, i. e., after severance of the slips.

The mechanism D comprises a pair of continuously rotating differential feed-rolls 12 and 13, provided with suitable trunnions 12^a and 13^a, respectively. A pair of journal members 14, mounted on the side-walls of the casing A, are provided with elongated slots 14^a, which serve as journals for the trunnions and permit a certain amount of relative movement between the rolls. The lower portions of the slots are equipped with springs 15 and plungers 15^a, which yieldingly support the roll 13 in its uppermost position. The rolls are also provided with collars 12^b and 13^b, which serve to keep the rolls in proper spaced relation.

The feed rolls 12 and 13 are provided with upraised spirals or threads 12^c and 13^c, respectively, and the threads 12^c are of the same length as threads 13^c but have less pitch and a smaller effective diameter (the diameter of the thread measured at its periphery). The threads are positioned so that when the rolls are rotated in opposite directions, at the same peripheral or surface speed, they will intermittently come into opposed relationship for one complete thread length and will exert a gripping and feeding action upon an interposed web, as illustrated in Figs. 2 and 4. When the threads are not directly opposed no gripping action is obtained as the paper will flex and the threads will slip over the paper as shown in Figs. 3 and 5.

While in the present embodiment each roll is shown with a right and left single thread, obviously more groups of threads and multiple threads may be used without departing from the spirit of the invention.

The crank shaft 9 is provided with a gear 16 which meshes with and drives a larger gear 17 of the cutter mechanism which in turn drives both of the feed-mechanisms B and D. The lower feed roll 3 of the main feed-mechanism B is provided with a pinion 18 which meshes with and is driven by the gear 17. The shaft 12 of the auxiliary feed-mechanism D projects through the journal 14 and casing A and provides a pivot for an idler gear 19 which is driven by the gear 17 and which in turn drives the pinion 20 mounted on the lower shaft 13. The shafts 13 and 12 are provided with intermeshing gears 21 and 22, which serve to rotate the spirals on the shafts at a uniform peripheral speed.

The crank 9^a, as shown in Figs. 6 and 7, has a slot 23 in its end portion to engage the latch 10 on every second revolution. The crank-shaft 9 is provided with a pinion 24 which meshes with and drives a cam-gear 25, which is pivotally mounted on the casing A and depresses a plunger 10^a which presses the latch 10 out of the path of the crank on its first revolution, as will be readily under-

stood from the drawings. A spring 26 is provided to keep the plunger 10^a in contact with the cam.

A pair of curved guide plates 27 and 28 are provided to direct the strip from the cutter mechanism C to the feed-mechanism D. A small transverse shelf 29 is attached to the casing wall to direct the slips from the rolls to a proper position in the compartment A⁴. If desired, the shelf may be pivoted at the edge nearest the feed roll and a cam-actuated arm provided to swing the shelf at proper times to assist in filing several slips.

Carbon strips (not shown) may be fed over the platen between the strips in any suitable manner.

As shown in Fig. 1, a bar 30 extends across the upper portion of the casing immediately back of the platen, just below the meeting place of the feed-rolls 2 and 3. The bar is slotted to accommodate the lower feed-disks and provides a tear-off edge 30^a on which copy slips may be severed from the lower strip of paper. Register pins 31 are provided to engage perforations with which the paper strips are provided, and thereby assist in positioning the strips, initially, over the platen.

To operate the machine, after the slips have been filled in, the latch 10 is depressed and the crank 9 rotated two complete revolutions, that is, until stopped by the latch 10. During this operation the lower strip 32 is drawn over the platen and projected downwardly through the chute E, and the upper strip designated 33 is projected by the main feed mechanism B under the cutter blade 11^a and down through the guides 27 and 28 to the auxiliary feed mechanism D. When the register perforations in the strips reach the feed disks at B the feeding will stop and the clamping bar 11 will be lowered and grip the upper strip while the blade 11^a descends and severs the slip. Just prior to the complete severance of the slip, the spirals on rolls 12 and 13 will come into opposed relation and draw the slip away from the blade down into the compartment A⁴.

Thus, it will be understood that the feed rolls of the auxiliary feed mechanism are continuously actuated and provided with deferred action slip-gripping means.

The foregoing detailed description has been given for clearness of understanding only, and no unnecessary limitations should be understood therefrom, but the appended claims should be construed as broadly as permissible, in view of the prior art.

What I regard as new, and desire to secure by Letters Patent, is:

1. Mechanism comprising a pair of feed rolls having different rates of rotation and equipped with strip gripping and feeding spirals which come intermittently into operative relation.

2. Strip-feeding mechanism comprising: feed rolls of different diameters equipped with spiral gripping devices adapted to come intermittently into gripping relation; and gears serving to drive said feed rolls at different rates of rotation.

3. Feed mechanism as specified in claim 2, in which the spirals of the rolls are of different pitches and of different effective diameters.

4. Strip-feeding mechanism comprising: a shaft having an upraised substantially helical thread; a companion shaft having a thread of less diameter and pitch but generated to conform with said first-mentioned thread when said shafts are rotated in opposite directions at a like peripheral speed; journals for supporting said shafts in spaced relation; and means for rotating said shafts in opposite directions at like peripheral speeds.

5. A device of the character set forth in claim 4, in which means are provided for yieldingly urging the shafts into juxtaposition and the shafts are provided with spacing collars.

6. A strip feeding device comprising: a pair of differential feed rolls; gear mechanism for rotating said rolls in opposite directions at like peripheral speeds; means for supporting said rolls in spaced relation; and means mounted on said feed rolls for gripping and feeding an interposed strip during certain revolutions of the rolls.

7. A device of the character set forth in claim 6, in which the gripping means comprise opposed helical bands similarly generated on the rolls.

8. A device of the character set forth in claim 6 in which the gripping means comprise opposed helical bands making at least one complete turn around their supporting feed rolls.

9. A strip-feeding device comprising: a pair of differential feed rolls, a plurality of threads mounted on one of said rolls, and a corresponding number of threads generated on the opposed feed roll so as to intermittently come into opposed relation with the first mentioned threads for one thread length when the rolls are rotated in opposite directions at like peripheral speed.

ALLEN B. COOKE.
